CLAIM

The ornamental design for a bottle cap grip, as shown and described.

DESCRIPTION

FIG. 1 is a top plan view of a bottle cap grip of the invention; FIG. 2 is a front elevation thereof, the rear elevation, right elevation, and left elevation all being identical;

FIG. 3 is a bottom plan view thereof; and,

FIG. 4 is a top perspective view thereof.

In the drawings, the broken lines show portions of a bottle cap grip that form no part of the claim.
